THERMOSTATIC VALVE FOR FUEL PUMPS
Alfred C. Korte, Jennings, Mo., assignor to ACF Industries, Incorporated, New York, N.Y., a corporation of New Jersey

Filed Dec. 30, 1960, Ser. No. 79,768
1 Claim. (Cl. 158—36.3)

This invention is directed to a fuel system and particularly to a fuel line pressure relief structure for use in a fuel system operative with internal combustion engines.

Conventionally, a fuel system for an internal combustion engine used, for example in a motor car consists of a source of fuel, such as a fuel tank, a carburetor for providing the appropriate emulsification of the fuel and its mixture with air prior to its use in the engine, and a pumping means for bringing the fuel from the fuel source to the carburetor. The pumping means normally is a diaphragm-operated fuel pump connected in a fuel line between the fuel tank and the carburetor. The diaphragm of the fuel pump is operated from a cam on the engine so that back and forth movement of the diaphragm provides a flow of fuel through a valve inlet and outlet from the fuel tank to the carburetor. Since the fuel pump is placed between the fuel tank and the carburetor the pump provides a sub-atmospheric pressure on the fuel in the line between the tank and the fuel pump and the atmospheric pressure on the surface of fuel in the fuel tank forces fuel from the tank to the fuel pump. However, beyond the fuel pump and between the fuel pump and the carburetor the fuel is moved by positive pressure from the pumping diaphragm.

In the design of cars, at the present time, the trend to lower hood lines and more compactness of the engine and its accessories under the hood, exposes the fuel system to the heat of the engine and ambient temperatures to a greater degree than was the case in previous years. The fuel in all parts of the fuel system is exposed to high temperatures such that there is a great tendency of the fuel to vaporize before it mixes with air in the carburetor. Such vapor conditions in the fuel system have been found very detrimental to efficient operation of the fuel pump and carburetor.

This vapor condition in the fuel system, which causes fuel vapor to be collected in the fuel lines and the fuel pump, is known as vapor lock. This condition limits the amount of solid fuel delivered to the carburetor by the fuel pump because of the great drop in the operating efficiency of the fuel pump. Under such conditions, the pump stays in operation but the presence of fuel vapor in the lines and in the pump allows the pressure of the pump to be dissipated or absorbed to an extent that only small amounts of fuel pass along the fuel line to the carburetor.

Not only is this condition of vapor lock accentuated by the high ambient temperatures which exist under certain operating conditions, but also, since the fuel in the line between the fuel tank and the fuel pump is under a sub-atmospheric pressure, there is a definitely greater tendency of the fuel to vaporize. Furthermore, the increase in the volatility of the fuel components in modern fuels has aided in the occurrence of this condition of vapor lock.

Besides the harmful effects of vapor lock on the pumping efficiency of the fuel pump, a vapor lock or vapor condition in the fuel line between the pump and carburetor is one which provides a difficult and hard starting of the engine after the engine has undergone a short period of "soak." Such a condition is that in which the engine, after being run at a fast rate for a period of time during hot weather, is stopped for a few minutes. Since the cooling system of the engine is inoperative, the stored heat in the engine as well as the hot ambient air prevents dissipation of the heat to the same extent as would be possible

2

if the engine were running and the car moving. Such a period in which the engine stands or "soaks" greatly increases the temperature of the fuel in the fuel system.

When a car is slowed down to a stop, the carburetor fuel bowl fills and the needle valve in the carburetor closes the fuel line from the pump. The pump then builds up the pressure of fuel in the line between the pump and the carburetor to a point where the fuel pressure holds the pump out of operation, since the fuel is pumped by spring action rather than a positive action from the pump driving cam of the engine. Thus, upon the stopping of the car, fuel between the carburetor and pump under the spring pressure of the pump will also be exposed to the ambient temperatures of a "soak" period to an extent that the fuel pressure will build up and force fuel past the needle valve of the carburetor into the fuel bowl. The added increase in the amount of fuel in the fuel bowl will permit the fuel to run out through the fuel nozzle into the intake manifold of the engine and, upon starting the engine, the excessive amount of fuel in the intake manifold results in a difficult starting of the engine.

It is therefore an object of this invention to provide a novel fuel supply system for an internal combustion engine in which the problem of vapor lock is minimized.

It is a further object of this invention to provide a novel fuel supply system in which the tendency of fuel in the system to vaporize under hot ambient conditions is minimized.

It is another object of this invention to provide a novel fuel system in which the tendency of vapor lock in the fuel system to reduce the efficiency of the fuel pumping means is minimized.

FIG. 1 is a schematic showing of a fuel system illustrating the invention and showing a fuel pumping means and a representative carburetor structure in elevation section.

FIG. 2 is a plan view of the pumping means of FIG. 1, with a portion of the inlet housing removed.

FIG. 3 is an enlarged sectional view of the vapor relief control means in accordance with the invention, and taken on section line 3—3 of FIG. 2.

FIG. 4 is an enlarged view of the spring element of the control means of FIG. 3.

Referring now to the drawing for a better understanding of the invention, the fuel system is shown as applied to a conventional internal combustion engine E having an intake manifold M. A carburetor is shown at 10 mounted on the engine E and having a fuel and air mixture conduit 12 with the lower end thereof connected to the inlet of the intake manifold M. The carburetor 10 in turn has a fuel inlet fitting 12 connected by a fuel conduit, represented by the dotted line 14, to a fuel pump structure 16. The fuel pump 16 has an inlet represented at 15 to which a fuel conduit, represented by the dotted line 20, connects the fuel pump 16 to a source of fuel consisting of a fuel tank 22.

The details of the carburetor 10 and the fuel pump 16 are somewhat conventional and well known and only those parts of these structures will be described for the understanding of the invention.

Fuel pump 16 consists of an inlet housing 24 in which there is formed with a valve housing 33 an inlet chamber 26 and an outlet chamber 28 separated by a transverse wall structure 29. The inlet housing 24 and valve housing 33 are fixed together with a gasket 35 between them by screws 37 (FIG. 2) extending upwardly from the valve housing 33 into the inlet housing 24. Gasket 35 is sealed across the outlet chamber 28 to form an air dome structure as shown in FIG. 1.

A flexible pumping diaphragm 39 is sealed around its periphery between a flange portion 32 of the pump body 45 and a flange 34 of the valve housing 33. Flanges 32

and 34 are held together by screws 31. To the center of pumping diaphragm 30 are mounted backing plates 36 and 38, respectively. To the centers of back plates 36 and 38 and tightly holding them together with pumping diaphragm 30 in between, is fixed one end 39 of a metallic stem 40, the other end 41 of which extends through a rubber gasket 42 into contact with a rocker arm 44 pivotally mounted on a rod bearing 46 in the lower portion of pump body 45. An end 48 of rocker arm 44 is kept in operative contact with one end of a push rod 50 mounted for sliding movement in a bearing 51 of engine E. Spring 52 between rocker arm 44 and the pump body 45 biases the rocker arm 44 into contact with rod 50, which in turn is oscillated in bearing 51 by virtue of its contact with a rotating cam 54 driven by the engine E.

The function of the rocker arm 44 is to load a spring 56 mounted between the clamping plate 38 and a flanged portion 57 of the body 45, as shown in FIG. 1. Rocker arm 44 has a slotted portion 58 which bears against the headed end of rod 40 and pulls rod 40 downwardly, as viewed in FIG. 1, to compress spring 56 as arm 44 is rocked in a counterclockwise direction. The downward movement of rod 40 moves pumping diaphragm 30 in an intake stroke. Rod 40 is released by the slotted arm portion 58 as the rocker arm is biased in a clockwise direction by spring 52 and spring 56 operates independently to force diaphragm 30 upwardly in a pumping stroke.

Pumping diaphragm 30 forms with the valve housing 33 a pumping chamber 60, which is connected by passages 62 to the inlet chamber 26 and by passages 64 to the outlet chamber 28, respectively. Closing passages 62 is a solid valve washer 66, which is spring-pressed upwardly, as viewed in FIG. 1, against the lower ends of passages 62 to provide an inlet valve to the pumping chamber 60. In a similar manner a solid valve washer 70 is spring-pressed downwardly to close off passages 64 and provide an outlet valve from the pumping chamber 60.

Upon operation of engine E, rod 50 and rocker arm portion 48 are reciprocally driven by cam 54 upwardly against the bias of spring 52, which in turn drives rod 50 downwardly and rocks arm 44 clockwise as cam 54 returns to its low point. The downward movements of rocker arm 44 will pull diaphragm 30 downwardly to suck fuel from the fuel line 20 and tank 22 into the inlet chamber 26 of the pump 16 and past valve 66 into the pumping chamber 60. Each time rocker arm 44 releases stem 40, the driving spring 56 forces diaphragm 30 upwardly and drives fuel out of the pumping chamber 60 past the valve 70 and through the pump outlet 25.

Fuel is thus forced into the carburetor inlet 12 and into a fuel bowl 74. A float 75 within fuel bowl 74 is pivotally mounted on a shaft 77 and is fixed to a valve operating lever 76 which contacts one end of a needle valve 78. A pointed head 80 of needle valve 78 opens and closes off the fuel passage through the inlet fitting 12 of the carburetor. When the level of fuel in bowl 74 reaches the desired predetermined amount, lever 76 will press against the needle valve 78 to close off the inlet passage to the carburetor. With needle valve 78 closed, pump spring 56 will be unable to drive diaphragm 30 in a pumping stroke, and the diaphragm 30 and rod 40 will be held in a downward position, as viewed in FIG. 1, by the pressure of fuel trapped between valve 66 and valve 78.

The other portions of the carburetor 10 are somewhat conventional and includes a calibrated orifice or jet structure 82, the passage of fuel through which is controlled by a tapered metering rod 84 operated by a piston and cylinder control sensitive to manifold pressure. Fuel passing through orifice 82 fills a well structure 86 to the level of the fuel in bowl 74. Within the mixture conduit of carburetor 10 there is formed a primary venturi structure 87 and a main venturi 88 to provide a drop in air

pressure to feed fuel from bowl 74 into passage 12 for mixture with air sucked into the manifold M of engine E. Because of the drop in pressure within the primary venturi 87, fuel in bowl 74, under atmospheric pressure, will be forced upwardly through a fuel tube 90 into the fuel nozzle 92, at which point fuel will enter the air stream passing into the manifold M. Additional air is mixed with the fuel before it leaves fuel nozzle 92 to provide an atomization of the fuel for optimum mixture with air in the mixture conduit 12.

A manually operated throttle 96 controls the flow of air through passage 12, while an unbalanced choke valve 98 pivotally mounted in conduit 12 provides for richer mixtures during cold operating conditions and for engine starting.

The operation of the fuel system shown in FIG. 1 is one in which, under cranking or operating conditions, the engine E drives the operating cam 54 in a manner described above for the operation of the fuel pump 16. The pumping of fuel from tank 22 into the pump inlet chamber 26 places the fuel in the conduit 20 under a sub-atmospheric condition, while fuel pumped from the pumping chamber 60 into the outlet chamber 28 and into the fuel line 14 places the fuel under normal pressures greater than atmospheric and something in the order of 5 to 6 pounds per square inch in a conventionally operating fuel pump. This pressure in fuel line 14 drops when the needle valve 78 opens to permit fuel flow into the fuel tank 74.

During the operation of the fuel system with an automotive vehicle in hot weather, the fuel tank is exposed to the radiated heat from the highway and to the relatively high ambient air temperature. This causes the temperature of fuel in the tank 22 to approach that of the ambient air or higher. Furthermore, the mounting of fuel pump 16 on the engine E with the fuel lines 20 and 14 adjacent to hot engine parts and also exposed to heat radiated from the engine causes the fuel in these lines to reach a higher temperature than that in the tank 22. The increased volatility of modern fuels together with these hot ambient conditions encourages vaporization of the fuel in lines 20 and 14, as well as in the various cavities of pump 16. Often, under such conditions, there occurs a vaporlock condition in which fuel vapors will collect in the fuel lines 20 and 14 and in the various pump cavities to hinder the normal flow of fuel from tank 22 to the carburetor 10 by action of the pumping of the fuel pump 16. An excessive amount of vapor in these portions of the fuel system greatly reduces the effectiveness of the pumping action of diaphragm 30 since the fuel vapor merely is compressed by action of the pump with little or no actual pumping of solid fuel through the fuel lines. The fuel in line 20 under a sub-atmospheric pressure will also tend to vaporize to a greater extent than normal and provide an additional source of fuel vapor in the system.

A vapor-lock condition often occurs during a hot stop or "soak" period of the engine. Under conditions of soak or when the engine has been driven at high speed under hot ambient conditions and then is allowed to stand inoperative for a period of time, the fuel between the inlet valve 66 of pump 16 and valve 78 of carburetor 10 will be under pressure as the fuel bowl will normally be filled and needle valve 78 closed. The pressure of the fuel in line 14 may also be increased by the bias of spring 56, if the drive rod 50 stops on a low position of cam 54. The conditions then are such that heat radiated and conducted from the engine as well as the ambient air temperature magnified by low hood lines will cause fuel in line 14 to increase in temperature and to the vaporization point. Valves 70 and 66 prevent the fuel from draining back through fuel line 20 into the tank 22, while closure of needle valve 78 prevents fuel and vapor from passing into the fuel bowl 74. However, as the pressure in line 14 builds up to an abnormal condition, fuel will be forced

past the needle valve 78 into the fuel bowl 74 to cause an overflow of bowl 74 out of the nozzle 92. This action dumps a quantity of raw fuel into the intake manifold M and prevents an easy starting condition when the engine is cranked.

The build-up of vapor in line 14 will reduce the efficiency of the pumping action of the fuel pump 16, as the vapor pockets in line 14 and in the outlet chamber 28 will absorb the fuel pressure exerted by pumping diaphragm 30 and will decrease the effective flow of pumped fuel to the carburetor 10. Furthermore, conditions in line 20 during a hot soak or during abnormally hot operating conditions and are such that the fuel, under sub-atmospheric pressure in line 20, readily vaporizes forming a foaming consistency of the fuel entering the inlet chamber 26 of the pump. The pump then merely pushes along a foamy mixture of fuel and vapor in which the amount of solid fuel is small, and under some conditions insufficient to operate the engine E. As the vapors build up in the pumping chamber 60, the pump takes longer and longer strokes because little fuel passes into the fuel bowl 74 and the float 75 stays down and allows the needle valve 78 to remain open. This drops the pressure in the pump chamber 60 and the outlet chamber 28 to reduce the effectiveness and efficiency of the pump.

In accordance with the invention, means are provided in the conduit from pumping chamber 60 to the carburetor 10 to correct and prevent the conditions of vapor lock or vapor accumulation in the fuel system. Such a device is disclosed in FIG. 2 and an enlarged showing is in FIG. 3. The invention is in the provision of an outlet passage 100 from the outlet chamber 28 of the pump, which passage 100 is connected by a fuel conduit line 102 to permit the flow of fuel from pumping chamber 28 in a return path to the tank 22. The passage 100 is fitted with a nipple 104, to which the conduit 102 is attached. Threaded into the outlet passage 100 is a valve seat structure 106 (FIG. 3) into which is fitted a calibrated orifice structure 108 to provide a predetermined flow of fuel into the conduit 102. The orifice structure 108 is partially closed by a valve device consisting of a valve element 110 formed by an enlarged head of a valve rod 112 slidably mounted in a bearing portion 114 of the valve seat structure 106. Fitted to a threaded end portion 116 of rod 112 is a shaped nut 118 having a peripheral groove 120 extending around its outer surface. The bearing portion 114 of the valve seat structure 106 also is formed with a circumferential groove 122 extending around its outer surface. A thermostatic spring 124 is coaxially mounted on rod 112 between the nut 118 and the bearing portion 114 of the valve seat structure 106. Spring 124 is a double wound helix formed of bimetallic spring material.

FIG. 4 shows spring 124 in an enlarged view. Spring 124 is formed of a thin bimetallic strip which is formed in a long helix and, then in turn, the helix is wound into a coil to form the convolutions of the spring. Each end of the bimetallic strip is formed into a shaped hook structure 130 which is fitted into one of the peripheral grooves 120 and 122, respectively. The valve head 110 is thus biased against a seat formed in the opening of orifice structure 108 by the spring 124 between the fixed bearing element 114 and the nut 118 on rod 112. Adjustment of the nut 118 will provide the desired biasing pressure of the valve head 110 against the valve seat 108. The bimetallic properties of the spring enable it to expand as the temperature of the fuel to which it is exposed in chamber 26 rises. Expansion of the spring 124 releases its biasing force on valve head 110. Further increase in fuel temperature will cause additional expansion of spring 124 to lift valve head 110 away from the valve seat of orifice 108. Valve head 110 has a small groove 126 in its surface to form a constant bleed from chamber 28 into the return fuel conduit 102.

The operation of the device is such that under normal

temperatures of the fuel in chamber 28 to which the thermostatic spring 124 is exposed, spring 124 will normally bias the valve head 110 onto the seat or orifice 108 and retain operation of the constant bleed 126 only. 5 Furthermore, the normal operating pressure of fuel in chamber 26 in the order of 5 to 6 pounds per square inch, aids in holding the valve 110 against its seat as well. This constant bleed 126, under normal conditions, has the effect of preventing any build-up of vapor in the outlet chamber 28. However, as the conditions for vapor lock 10 occur, the fuel and vapor mixture within the pump takes on a frothy consistency and the mixture becomes heated because of the adverse operating conditions. As the 15 temperature of the fuel rises in the outlet chamber 28 of the pump, the spring 124 will tend to expand to first relieve its biasing pressure on the valve 110 and then to overcome the pressure of the fuel itself tending to hold the valve 110 against its seat. As the valve 110 moves away from its seat, the passage of fuel into the return line 20 102 is increased and it has been found that the fuel vapor escapes through return line 102 more readily than the solid fuel itself. Thus during pump operation, opening of the by-pass under abnormally hot conditions will eliminate vapors in the pump and permit a greater flow of 25 solid fuel through the pump, which in turn clears out other vapors trapped in the various chambers of the pump. Larger quantities of solid fuel, which can now pass through the pump, exert a cooling action on the pump itself and retains this portion of the system at lower operating 30 temperatures.

The device, thus described, forms a thermostatically controlled relief valve in which the valve is controlled by a thermostatic heat-responsive spring exposed to the temperature of the fuel in the output portion of the pump. 35 The device is one which provides a large by-pass of vapors back to the tank when it is needed under adverse conditions of high temperature. During the shutdown of the engine and under hot soak conditions, the constant bleed 126 will also correct the build-up of pressure in line 14 between the pump and the carburetor to prevent flooding of the carburetor fuel bowl. This bleed thus provides a relief of line 14 back to the fuel tank, since under such conditions the valve 70 in the pump is closed.

Under one condition of operation, the spring 124 was 45 adjusted to open valve 110 at approximately 115° F. when the fuel pressure within chamber 28 was around 5 to 6 pounds per square inch. At this temperature and pressure, the fuel has various light ends which will vaporize to a great extent above 100° F. At the predetermined 50 temperature above 100° F., the thermostatic spring 124 will open and by-pass fuel vapor back to the tank 22.

The opening of valve 110 will take place at different temperatures in accordance with changes in the pressure of the fuel in the outlet chamber 28. As described above, 55 the fuel pressure within chamber 28 exerts a closing force on the valve 110, which has to be counteracted by expansion of a thermostatic spring 124 to open valve 110. Under adverse conditions of high temperature operation, the presence of vapor in the outlet chamber 28 of the 60 pump causes the pump pressure in chamber 28 to drop. This drop in fuel pressure reduces the closing force of the fuel on valve 110 and permits its opening by spring 124 at a lower temperature.

The bleeding of fuel vapor through the fixed bleed 65 126 or through the open valve 110 contributes to a greater efficiency of pump operation as the output pressure in chamber 28 is prevented from building up to produce a back pressure against the pumping stroke of diaphragm 30.

I claim:

70 A fuel system for an internal combustion engine, said system comprising a source of fuel, a carburetor, a fuel conduit means connecting the source of fuel and the carburetor, fuel pumping means including a diaphragm pump for delivering fuel from said source to said carburetor forming a part of said fuel conduit means, a return fuel

by-pass means connecting said fuel pumping means and said fuel source, valve means normally closing said by-pass, temperature responsive means located in the flow path of said fuel in said fuel conduit to bias said valve means towards open position upon a predetermined rise in fuel temperature, and a normally open restricted bleed about said valve means to permit a limited flow of vapor from said pump into said by-pass when said valve means is in closed position to prevent the build up of pressure in said pump.
